(57) CLAIM

The ornamental design for a pill storage case, as shown and described.

DESCRIPTION

FIG. 1 is a front view of a pill storage case showing my new design.

FIG. 2 is a back view of the pill storage case.

FIG. 3 is a side view of the pill storage case.

FIG. 4 is a top view of the pill storage case; and,

FIG. 5 is a bottom view of the pill storage case.

The broken line showing of environment in the drawings is for illustrative purposes only and forms no part of the claimed design.
